CLAIM

The ornamental design for a resin structure roof section, as shown and described.

DESCRIPTION

FIG. 1 is a perspective view of a resin structure roof section showing my new design;

FIG. 2 is a front view thereof, the back view being identical; FIG. 3 is a right side view thereof, the left side view being identical;

FIG. 4 is a perspective view of a second embodiment of a resin structure roof section showing my new design;

FIG. 5 is a front view thereof, the back view being identical; and,

FIG. 6 is a right side view thereof, the left side being identical.

The phantom line representations in FIGS. 1-6 are exemplary and form no part of the invention.
